UNITED STATES PATENT OFFICE.

HILAND H. KENDRICK, OF FULTON, NEW YORK.

WATER-CLOSET.

SPECIFICATION forming part of Letters Patent No. 664,559, dated December 25, 1900.

Application filed March 10, 1899. Serial No. 708,481. (No model.)

To all whom it may concern:

Be it known that I, HILAND H. KENDRICK, a citizen of the United States, and a resident of Fulton, in the county of Oswego, in the State of New York, have invented new and useful Improvements in Water-Closets, of which the following, taken in connection with the accompanying drawings, is a full, clear, and exact description.

10 This invention relates to the class of water-closets in which the flushing of the bowl is effected automatically.

The invention consists in the novel construction and combination of parts herein-
15 after described and claimed.

In the accompanying drawings, Figure 1 is a side elevation of a water-closet embodying my invention. Fig. 2 is a vertical sectional view of a slightly-different construction.

20 Fig. 3 is a front view of the bowl and its appurtenances. Fig. 4 is a plan view of the same. Fig. 5 is a longitudinal section of the cable-inclosing tube to which cable-guiding sheaves are pivoted. Fig. 6 is a top plan view of said section. Fig. 7 is an enlarged vertical section on line xx in Fig. 2. Figs. 8 and 9 are vertical sectional views of the supply-valve, taken in a plane at right angles to the axis of the valve. Fig. 10 is an enlarged side view of one of the elbows of the pipe which incloses the actuating-cable, the front panel being removed to illustrate the arrangement of the sheave in said elbow. Fig. 11 is a side view of said detached front panel, and Fig. 12 is an enlarged transverse section of that portion of the pulley to which the cable is clamped and shows the means for clamping the cable to the pulley.

35 Similar letters of reference represent corresponding parts.

40 A represents the bowl of the water-closet, which bowl may be of any suitable shape, preferably formed with the outlet-spout a at the rear of its bottom. To the lower end of this spout is connected the soil-pipe P , which is extended a considerable distance beneath the bowl and to a suitable place where it is protected from freezing and where it has attached to it a suitable trap P' .

45 B denotes a ventilating-pipe leading from the rear portion of the bowl.

C represents the flushing-pipe, which com-

municates with the bowl A , preferably near the top of the rear side of the bowl, as shown. This flushing-pipe may be extended either to 55 the usual flushing-tank D , as shown in Fig. 1 of the drawings, or to a valve V , which is connected directly to the water-supply pipe F , as represented in Fig. 2 of the drawings, in which latter case the aforesaid flushing- 60 tank is dispensed with. From said valve extends also a waste-pipe I directly to the soil-pipe P above the trap P' .

The valve V may be of any suitable shape. I prefer, however, to employ an annular valve 65 pivoted in a correspondingly-shaped cage V' , which is provided with three ports, the first of which is for the water-supply pipe F , the second for the flushing-pipe C , and the third for the waste-pipe I , which leads directly to 70 the soil-pipe P .

The valve V consists of a hollow annular plug the peripheral wall of which is provided with two ports b and b' for admission of water through the interior of said plug, as shown 75 in Figs. 8 and 9 of the drawings. The port b is of such a width as to invariably maintain the flushing-pipe C in communication with the interior of the valve while said valve is turned in either direction. The other port 80 b' is narrower and in such a position as to open the waste-pipe I when the supply-pipe F is closed, as represented in Fig. 8 of the drawings, and thus the flushing-pipe C communicates with said waste-pipe. In turning 85 the valve into the position shown in Fig. 9 of the drawings the waste-pipe is closed and the port b opens communication between the supply-pipe F and flushing-pipe C . Into this latter position the valve is turned automatically 90 with movement of the cover T to its open position, as hereinafter described.

To control the flow of water through the flushing-pipe C automatically, I employ the following mechanism, to wit: Upon the usual 95 seat S of the bowl A is the cover T , fastened at its rear edge to a transverse shaft c , which passes through brackets $d d$, secured to a stationary plate d' back of the seat. (See Fig. 4 of the drawings.) To this shaft is pivoted 100 the seat S by means of ears $e e$, attached to said seat and receiving the shaft through them. To the cover T are attached ears ff , which likewise receive said shaft through

them, but are fastened thereto by set-screws f' or other suitable means. To the end of the shaft c is firmly secured either a pulley or chain-wheel L , upon which is mounted a cable or chain h , the ends of which are attached to the free ends of arms i , fastened to the axis of the valve V and extending in opposite directions therefrom. Said chain or cable is secured in such a position on the wheel 5 or pulley L and arranged in such relation to the arms i as to cause one end of the chain or cable to turn the valve V into a position to establish communication between the water-supply pipe F and flushing-pipe C when 10 the cover T is lifted to its open position, as illustrated, respectively, in Figs. 9 and 2 of the drawings. It is therefore obvious that the bowl A is flushed invariably while the closet is in use. The bowl is thus constantly 15 rinsed during that time, and the rinsing passes off freely through the outlet-spout a into the soil-pipe P and thence through the trap P' , which effectually prevents gases and odor from rising above the trap. In lowering the 20 said cover to its closed position, as indicated by dotted lines in Fig. 2 of the drawings, the opposite end of the aforesaid chain or cable is caused to turn the valve V into a position to cut off the flow of water from the supply- 25 pipe F to the interior of the valve and at the same time open the port to the waste-pipe I , as shown in Fig. 8 of the drawings, thus allowing the water in the flushing-pipe C to recede through the valve and waste-pipe to 30 the soil-pipe. The flushing-pipe therefore 35 remains empty until the cover T is again raised.

It will be observed that by the connection of the cover T with the valve-actuating devices 40 the valve is controlled independently of the seat S , and therefore the hinging of said seat to the closet is immaterial in my invention, which is thus rendered applicable to a closet having a stationary seat.

45 In order to properly guide and protect the aforesaid chain or cable, I inclose the same in a suitable tube l and arrange therein sheaves n , upon which the two end portions of the chain or cable run. To afford access to said 50 sheaves for adjusting or repairing or renewing the same when required, I provide the tube l with removable panels l' and mount each pair of sheaves loosely on a pin o , which is secured at one end to the side of the tube 55 and passes with its opposite end through the panel l' and has fastened to its protruding end a suitable head o' , which laps onto the panel, as shown in Fig. 5 of the drawings.

My invention is applicable to water-closets 60 which are equipped with the usual flushing-tank D , as represented in Fig. 1 of the drawings, in which case I form the flushing-pipe of two sections C and C' , the section C' extending from the valve V to the tank to supply the 65 same with water, and the other section C extends from said tank to the bowl A and is provided with a suitable valve t , which is lifted

automatically from its seat on the inlet to the pipe-section C by means of a chain g , connecting said valve to one end of a lever j , the opposite end of which is connected by a chain g' to a lever j' , fastened to the shaft c in such a position as to cause the lever j' to draw down the chain g' when the cover T is lowered to its closed position on the seat S , thereby causing the water to flow from the tank D through the flushing-pipe C to flush the bowl A until the tank D is emptied. Said tank remains empty until the cover T is again raised, which causes the chain g' to be slackened to allow the valve 70 t to drop to its seat to close the flushing-pipe C . At the same time said movement of the cover T turns the valve V to cause the water to pass from the supply-pipe F through said valve and to the tank D to fill said tank until 75 cut off by the usual float-valve D' in said tank. In this arrangement it may be desired to continue a small stream of water into the bowl A during the time the tank D is being filled and the seat is occupied. To permit such a 80 stream, I connect the pipe-section C' directly with the pipe-section C by a small pipe p , provided with a valve p' , as represented in Fig. 1 of the drawings. The flushing of the bowl may be controlled by hand in the usual manner 85 when desired by a pull upon the chain g' and holding the same during the time of flushing.

In order to permit access to the interior of the bowl A for repairs or other purposes in which the flushing of the bowl is not desired, 90 I provide adjustable means for fastening and releasing the cable h to and from the pulley L . One of said means is illustrated best in Fig. 12 of the drawings, and consists of two clamping-bars r and r' , placed, respectively, 95 across the inner and outer sides of the rim of the pulley and made to press the cable onto the pulley by means of bolts u , passing through the ends of said bars and provided with nuts which may be loosened when desired for the 100 aforesaid purpose. Said releasing of the cable is to be effected while the cover T is closed, thus leaving the valve V in position to cut off the water from the flushing-pipe.

It is obvious that my described automatic 105 flushing apparatus is applicable to water-tanks of various kinds.

What I claim as my invention is—

1. The combination with the bowl, its hinged cover, soil-pipe, flushing-pipe, and a 110 water-supply valve disposed out of direct range with the flushing-pipe, of a pulley fastened to the axis of the cover to be actuated thereby, a cable or chain attached intermediate its ends to said pulley and having its 115 ends connected to the valve to operate the same, pipes extending from the valve toward the bowl and inclosing said cable or chain, said pipes having elbows provided with detachable panels to afford access to the interiors thereof, and sheaves pivoted in said elbows and guiding said cables or chains, as set forth.

2. The combination with the bowl, its

hinged cover, and soil-pipe, of a valve-cage having three ports, a supply-pipe leading to one of said ports, a flushing-pipe leading from another of said ports, a waste-pipe leading from the third port to the soil-pipe, a plug in said cage, having laterally-projecting arms, a device fixed on the axis of the cover, a cord or chain secured between its ends to said device and having its ends secured to the respective valve-arms, so as to turn the valve in one direction when the cover is raised and in another direction when the cover is lowered, sheaves over which said cord or chain passes, and a pipe to contain said cord or chain and sheaves, said pipe having detach-

able panel to afford access to the sheaves and cord or chain, and said plug having a port which opens communication of its interior with the waste-pipe when the cover is closed and also having an enlarged port which maintains the flushing-pipe constantly in communication with the interior of the plug and opens communication of the supply-pipe with the interior of the plug only when the cover is raised. 20
